INKING MECHANISM FOR PRINTING PRESSES

Robert Michle, Chicago, Ill.; Mabel K. Michle, administratrix of said Robert Michle, deceased

Application June 8, 1931, Serial No. 542,760

33 Claims. (Cl. 101—357)

My invention relates particularly to reciprocating bed and cylinder printing presses and has for its main object the provision of a novel, convenient and effective inking mechanism for this type 5 of printing press which adequately and uniformly inks the printing form without necessitating an excessive distance of bed travel or, conversely, which adequately and uniformly inks a relatively long form with a given distance of bed travel.

With this object in view my invention consists 10 in certain features of novelty in the construction, combination and arrangement of parts by which the said object and certain other objects, hereinafter appearing, are effected, all as fully described 15 with reference to the accompanying drawings and more particularly pointed out in the appended claims.

In the said drawings—

Figure 1 is a partial side elevation of a printing 20 press embodying my invention with parts broken away and shown in section;

Figure 2 is a partial transversely condensed end elevation of the same with parts broken away and shown in section;

Figure 3 is another partial side elevation of the same with parts broken away and shown in section; and

Figures 4 and 5 are diagrammatic views of the same in side elevation;

Figure 6 is a partial end elevation of the reciprocating bed with parts broken away and shown in section; and

Figure 7 is a partial top plan view of one side of the ink roller frame structure, hereinafter described.

Like characters of reference indicate like parts in the several views.

Referring to the drawings, 1 designates a two revolution impression cylinder and 2 designates a reciprocating bed which carries a form 3 from which sheets on the impression cylinder are printed during stroking of the bed in the rearward direction, i. e., to the left in Figures 1, 3, 4 and 5, the cylinder rotating in a corresponding direction and being lifted out of contact with the form during forward stroking of the bed, all as is usual.

Figure 1 shows the bed at the beginning of its printing stroke while Figure 3 shows the bed at the end of the printing stroke preparatory to its forward or non-printing stroke.

The main frame of the press includes usual side frames 4, and the bed 2 is reciprocated by a suitable reciprocating mechanism, not shown, while the cylinder 1 is driven in timed relation with the

bed by gearing which is inclusive of a gear 5 mounted on the shaft of the cylinder and rotatably secured therewith by means of a headed screw 6 passing through a hole through the web of this gear and screwthreaded into one of two angularly spaced holes 7 in a disk 8 secured on the cylinder shaft whereby the cylinder may be shifted angularly with reference to its timing with the bed for purposes hereinafter described. See Figures 1, 2 and 3.

Mounted on the rear ends of the side frames 4 are feed board frames 9, lower portions 11 of which extend forwardly and support an ink fountain 12, which is inclusive of a fountain roller 13, spaced upwardly from the plane of the bed 2 and under which the bed passes. Arranged between the lower portions 11 of the feed board frames and the cylinder 1 is a rear form roller frame comprising frames 14 arranged at opposite sides of the bed and secured at their rear or outer ends to a transverse shaft 15 which is journaled on the lower portions 11 of the feed board frames for pivotal movement of the rear form roller frame vertically. See Figure 3.

Arranged forwardly of the cylinder 1 is a front form roller frame comprising transversely spaced frames 16 arranged at opposite sides of the bed and having their front or outer ends coaxially pivoted on the adjacent side frames 4, as designated at 17, for pivotal movement of the front 20 roller frame vertically. See Figures 1 and 2. The frames 14 and 16 are provided with downwardly extending legs 19 which engage downwardly on the side frames 4 to limit downward movement of the roller frames.

Mounted on each form roller frame, by means of suitable adjustable sockets or fork bearings 21, is a group of composition form inking rollers 22, as shown each group comprising four, and when each form roller frame is in its lower position, as determined by the legs 19 thereof engaging downwardly on the side frames 4, its form rollers engage the form 3 on the bed 2, and roll thereon to ink the same during reciprocation of the bed.

The form roller frames are provided with upwardly extending supports 24 between the axes of the outer form rollers and those of the form rollers adjacent thereto, and pivotally mounted on these supports above the form rollers are 40 distributor roller frames comprising transversely spaced frames 25 secured on transverse shafts 26 which are journaled on the upper ends of the supports 24. The lower positions of the distributor roller frames with reference to the form 50 55

roller frames are determined by abutting lugs 27 on these frames, and the form and distributor roller frames are locked in this relative position by hand operated hook levers 28 pivoted inwardly 5 on the form roller frames and engaging over studs 29 on the inner ends of the distributor roller frames.

Release of the levers 28 from the studs 29 permits upward movement of the distributor 10 roller frames to separate the distributor rollers, hereinafter described, carried by the distributor roller frames from the form rollers 22 carried by the form roller frames, as shown in broken lines in Figures 1 and 3.

15 The front distributor roller frame is maintained in its upper or separated position by a stud 31 on one of the supports 24 of the front form roller frame being engaged by this distributor roller frame in over center position, as 20 shown in Figure 1.

The rear distributor roller frame is maintained in its upper or separated position by a hook 32 pivoted on the rear distributor roller frame and engageable over a transverse shaft 33 journaled 25 on the upper ends of the supports 24 of the rear form roller frame for purposes hereinafter described, the hook being released from this shaft to permit movement of the rear distributor roller frame to its lower position. See Figures 3 and 7.

30 The distributor roller arrangement for the form rollers at the rear of the cylinder is as follows. See Figures 1 and 3.

A metal vibrator distributor roller 34 is carried by the rear distributor roller frame and contacts the intermediate pair of the rear form rollers, and a second metal vibrator distributor roller 35 also carried by the rear distributor roller frame contacts the inner roller of the rear form rollers but does not contact the form roller adjacent said inner form roller. A composition distributor roller 36 also carried by the rear distributor roller frame contacts both of the distributor rollers 34 and 35.

A metal distributor roller 37 of relatively small 45 diameter contacts the outer pair of the rear form rollers and has its axis disposed in the region of the axial plane of the form rollers to permit the removal and installation of the adjacent form rollers without disturbing this distributor roller. 50 Bearings 38 carry the distributor roller 37 and are journaled on the aforesaid shaft 33, and are accordingly mounted on the supports 24 of the rear roller frame for pivotal movement for adjustment of the roller 37 in directions corresponding with the axial plane of the form rollers 55 particularly to accommodate for the adjustment of the inner form roller contacted by the roller 37 to the distributor roller 34.

The distributor roller arrangement for the form 60 rollers at the front of the cylinder is as follows. See Figure 1.

A metal vibrator distributor roller 41 is carried by the front distributor roller frame and contacts the intermediate pair of front form rollers, 65 and metal distributor rollers 42 of relatively small diameter contact respectively the outer and inner pairs of front form rollers and have their axes disposed in the region of the axial plane of the form rollers to permit the removal and installation 70 of the adjacent form rollers without disturbing these distributor rollers. Bearings 43 carry the distributor rollers 42 and are mounted, as designated at 44, for pivotal movement for adjustment of the rollers 42 in directions corresponding with the axial plane of the form rollers 75

particularly to accommodate for the adjustment of the intermediate pair of front form rollers to the distributor roller 41, the bearings 43 of the outer roller 42 being mounted on the supports 24 of the front form roller frame and the bearings 43 of the inner roller 42 being mounted on upwardly extending supports 45 on the front roller frame and disposed between the axes of the inner pair of front form rollers.

Secured on the shaft 26 of the rear distributor 10 roller frame are transversely spaced bearing arms 46 which extend upwardly and forwardly from this shaft and have at their upper ends slot bearings 47 which tilt rearwardly and downwardly. See Figures 1 and 3. A metal roller 48 of relatively small diameter is mounted in the slot bearings 47 for rotation and movement along these slot bearings into and out of contact with the distributor roller 36, the roller 48 being yieldably urged rearwardly out of contact with the roller 36 by reason of the rearward and downward inclination of the bearing slots, as shown in Figure 3.

A composition ductor roller 49 is mounted at the 25 free ends of transversely spaced arms 51 which are secured on the aforesaid shaft 33 which is journaled on the supports 24 of the rear form roller frame above the rear form rollers and immediately to the rear of the rear distributor roller frame shaft 26. As so carried the ductor roller 49 is movable to alternately contact the roller 13 of the ink fountain 12, see Figure 3, and the roller 48 and to periodically move this roller 30 into contact with the distributor roller 36 for the transfer of ink from the ductor roller to the roller 48 and from it to the distributor roller 36. As the ductor roller moves toward the ink fountain, the roller 48, under the influence of gravity, moves rearwardly in the slot bearings 47 out of 35 contact with the roller 36.

The rear ends of the slot bearings 47 are provided with cushioning elements 52, such as leather, to cushion the roller 48 at the rearward end of its movement, and these bearings are open at the top, as shown, for the removal and installation of this roller.

The shaft 33 is oscillated from the press mechanism in timed relation therewith in a usual manner not shown, to alternately contact the fountain roller 13 and the roller 48 and to periodically contact the roller 48 with the distributor roller 36.

The roller 48 serves in the nature of an additional distributor roller and being of relatively small diameter serves to break up the ink in transferring it onto the distributor roller 36.

The distributor and form rollers are driven with the bed, as hereinafter described, and preferably, the ductor roller 49 contacts the roller 48 and moves it into contact with the distributor roller 36 when the bed is at the front end of its movement, as shown in Figure 1.

This condition is maintained throughout a portion of the rearward or printing stroke of the bed, and during this movement of the bed the distributor roller 36 rotates in the direction, i. e., clockwise in Figure 1, to first bring the fresh supply of ink into contact with the distributor roller 35 which supplies the inner form roller of the rear group, with the result that this form roller receives the greatest supply of ink for transfer to the form. This tends to insure a good supply of ink forwardly on the form, so that the front form rollers receive an adequate supply of ink, as hereinafter described.

The pivot mounting of the ductor roller carrier, 75

comprising the arms 51 secured on the shaft 33 which is journaled on the upper end of the supports 24 of the rear form roller frame above the rear form rollers, is independent of and spaced from the ink fountain 12 which is adjacently spaced outwardly and upwardly from the outer roller of the rear form rollers. Accordingly, space is provided for the removal and installation of this outer form roller vertically past the ink fountain when the ductor roller 49 is positioned away from the fountain as shown in Figure 1. To this end the fork bearings or sockets of this outer form roller are extended obliquely upward, as designated at 55, to guide this form roller in its installation and removal.

The bed 2 is provided with a downwardly facing rack 56 on its under side, and a transverse shaft 57, disposed in the region of the mid point of the travel of the bed, and preferably, as shown, disposed rearwardly of the axial plane of the cylinder normal to the bed, is journaled on the press frame and has a gear 58 secured on its inner end, which meshes constantly with the rack 56, so that the shaft 57 is rotated in one direction with the travel of the bed in one direction and is rotated in the opposite direction with the travel of the bed in the opposite direction.

Secured on the outer end of the shaft 57 on the outside of one of the side frames 4 is a gear 59 which meshes with an idler gear 61 which is rotatably mounted on a bracket 62 secured downwardly on the adjacent side frame 4 rearwardly of the cylinder 1.

The distributor rollers 34 and 35 of the rear roller group have gear pinions 63 secured on ends thereof, which mesh with the gear 61, so that the rear roller group is driven with the bed, the pinions 63 disengaging from the gear 61 when the rear distributor roller frame is moved to its upper position, as hereinbefore described, and engaging the gear 61 when this distributor roller frame is moved into its lower position.

Secured on the side frame 4 adjacent the gear 59 is a bracket 64 upon which two meshing idler gears 65 and 66 are rotatably mounted. The gear 65 meshes with the gear 59, and an idler gear 67, rotatably mounted on a bracket 68, secured downwardly on the adjacent side frame 4 forwardly of the cylinder 1, meshes with the gear 66 so that the gear 67 is driven from the bed in the same manner as is the gear 61. The distributor roller 41 of the front roller group has a gear pinion 69 secured on an end thereof which meshes with the gear 67 so that the front roller group is driven with the bed, the pinion disengaging from the gear 67 when the front distributor roller frame is moved to its upper position, as hereinbefore described, and engaging the gear 67 when this distributor roller frame is moved into its lower position.

Accordingly, both front and rear roller groups are driven with the bed through the gear 58 meshing with the rack 56, it being observed that the rack is accordingly relatively short and where, as shown, the gear 58 and its shaft 57 are disposed in the region of the mid point of the bed travel, the rack does not extend unduly beyond the ends of the bed. See Figure 3.

Neither the front or rear group of form rollers 22 completely covers the form 23 on the bed, so that at each reversal of the bed one group is above the form. In order that there be no tendency of the form rollers to wipe the form at the reversals of the bed the following is provided.

As hereinbefore described, the front and rear

form roller frames are pivotally mounted for vertical movement, their lower positions in which the form rollers engage the form being determined by the legs 19 engaging downwardly on the side frames 4.

Arranged on opposite sides of the bed 2 adjacent respective ends thereof are aligned pairs of rollers 71 which are mounted on the bed by means of slotted head eccentric studs 72 secured in angularly adjusted position in bores in the bed by set screws 73 screwthreaded in the bed so that the vertical position of the rollers may be adjusted. See Figures 2, 3 and 6.

The pairs of rollers 71 are offset transversely, as will be seen in Figures 2 and 6, and the inner ends of the front form roller frames 16 are provided with downwardly facing cam formations 74 aligned with the pair of rollers 71 adjacent the rear end of the bed, while the inner ends of the rear form roller frames 14 are also provided with downwardly facing cam formations 74 aligned with the pair of rollers 71 adjacent the front end of the bed. The rear pair of rollers 71 and the cam formations 74 of the front form roller frames 16 are nearest the side of the bed and these cam formations are connected with the front form roller frames by a connecting portion 76 disposed above the rollers 71 adjacent the front of the bed to clear the same, the cam formations 74 of the rear form roller frames 14 clearing the rollers 71 adjacent the rear of the bed by reason of these cam formations being disposed outwardly of these rollers.

In operation, each pair of rollers 71 engage their cam formations 74 to lift the corresponding form roller frame and with its form rollers to disengage the same from the form at the reversal of the bed in which the form underlies its form rollers, as shown at the left in Figure 1 and at the right in Figure 3, each form roller frame and its form rollers being restored to its lower position to re-establish engagement of its form rollers with the form immediately after the reversal.

The form rollers are maintained in contact with the distributor rollers during the disengagement of the form rollers with the form during reversals of the bed, each form and distributor roller group being lifted and lowered as an operative unit, and, the lift not being great enough to disengage the pinions 63 from the gear 61 or the pinion 69 from the gear 67, the form and distributor roller groups are reversed with the bed.

The axis of movement of the rear form roller frame, i. e., that of the shaft 15, is so disposed that an arc on this axis and passing through the axis of the gear 61, designated at 75 in Figure 3, passes between the axes of the pinions 63, so that the rotative tendency of the pinions 63 due to their bodily movement with reference to the gear 61, while in mesh therewith, as the rear roller group is moved on the axis of the shaft 15 is not great and is more or less equalized, so that it is not detrimental.

The axis of movement of the front roller frame, i. e., that of the pivots 17, is so disposed that an arc on this axis and passing through the axis of the gear 67, designated at 80 in Figure 1, passes adjacent the mesh point of the gears 67 and 69, so that the rotative tendency of the gear 69 due to its bodily movement with reference to the gear 67, while in mesh therewith, as the front roller group is moved on the axis of the pivots 17 is not great, so that it is not detrimental.

Journaled in a bore through one of the side frames 4 is a transversely disposed eccentric shaft 75

76 which underlies a leg 19 of the rear form roller frame. See Figures 1, 2 and 3. This shaft is provided with a hand crank 77 on the outside of the side frame, and the side frame is provided with 5 stops 78 engageable with the hand crank to limit angular movement of the eccentric shaft.

When the eccentric shaft 76 is at one end of its movement the rear form roller frame may assume its lower position in which the rear form rollers 10 contact the form, as shown in Figure 1. When the eccentric shaft 76 is in its opposite position the rear form roller frame is positioned in its upper position in which the rear form rollers are out of contact with the form, as shown in Figure 3. 15 While not shown, it is obvious that a duplicate eccentric shaft device may be placed on the other side of the machine to obviate torsional strain on the rear form roller frame, both eccentric shafts being positioned correspondingly.

20 Journalized on and extending across between the side frames 4 below the pivots 17 is a transverse shaft 79 which is disposed below the plane of the bed 2, and secured on this shaft immediately inside of the side frames 4 are aligned eccentric collars 81. See Figures 1 and 2.

Secured on the shaft 79 on the outside of one of the side frames is a handle 82, and this side frame is provided with stops 83 engageable by the handle to limit angular movement of the shaft 79.

30 The front form roller frames 16 are provided with arms 84 extending downwardly from the pivots 17 thereof, the lower ends of which arms are engageable by the eccentric collars 81. Accordingly, when the shaft 79 is at one end of its movement the front form roller frame may assume its lower position in which the front form rollers contact the form, as shown in Figure 3. When the shaft 79 is in its opposite position the upper form roller frame is positioned in its upper 35 position in which the front form rollers are out of contact with the form, as shown in Figure 1.

Thus are provided manually controlled means for positioning the form rollers out of contact with the form during prolonged stops of the press 45 and for another purpose hereinafter set forth, the eccentric shafts 76 and 79 being preferably manipulated to position the form roller frames in their upper positions while the press is running so that the rollers 71 cooperating with the 50 cam formations 74 do the actually lifting of the form roller groups and their frames.

As hereinbefore set forth, neither group of form rollers 22 completely covers the form 23. The groups of form rollers at the front and rear of 55 the cylinder overlap in their contact with the form, and the ink fountain 12 constitutes the sole source of ink supply to all of the form and distributor rollers, and, as shown, the form constitutes the sole source of ink supply for the form 60 and distributor roller group at the front of the cylinder, the form receiving ink from the rear form rollers and the front form rollers taking up ink from the portion of the form on which the front and rear form rollers overlap and reapplying 65 it to the form particularly to that portion of the form not contacted by the rear form rollers.

The ink taken up from the form by the front form rollers is distributed thereon by the distributor rollers 41 and 42 so that the ink is applied uniformly.

Both the front and rear groups of form rollers are each sufficient in number to adequately ink the form, so that both groups combine in adequately inking the form throughout, as shown the 75 entire form being contacted by at least four form

rollers, and a great portion of it by more. This is shown in Figure 4 in which the bed is shown at the rear end of its movement in unbroken lines and at the front end of its movement in broken lines.

The present accepted standard of inking apparatus, for reciprocating bed and cylinder printing presses, adequate for all classes of printing involves four form inking rollers completely covering the form with the requisite number of form 10 roller distributor rollers together with four ink table distributor rollers contacting an ink table carried with the bed, which arrangement involves a relatively long bed travel and a corresponding relatively long machine. The inking 15 device of my invention provides as good, if not better, inking with a relatively short bed travel and a corresponding relatively short machine, and without necessitating a greater number of inking rollers.

20 The ink fountain 12 supplies a sufficient quantity of ink to the rear roller group for inking the entire form, and, due to the fact that the rearward stroke of the bed is the printing stroke, ink applied to the form by the rear form rollers is 25 transferred to the front form rollers on the forward or non-printing stroke of the bed without the printing impression intervening, so that an adequate supply of ink is transferred to the front form rollers. Accordingly, the entire form is adequately inked with a relatively short stroke of the bed, or, conversely, a relatively long form is adequately inked in a given stroke of the bed.

30 In certain classes of work where a shorter form is used, it is desirable that the form roller of the front group nearest the cylinder, which is the last roller to roll over the form previous to impression, shall completely cover the form. Accordingly, see Figure 5, the shorter form, designated at 85, is positioned on the bed so that the rear or gripper 35 end of the form is forward of the form roller of the front group nearest the cylinder when the bed is at the front end of its movement.

To correspond the timing of the sheet grippers 36 of the cylinder with this position of the rear or gripper edge of the form, the cylinder is shifted angularly with reference to its timing with the bed from an advanced position, as shown in Figures 1, 3 and 4, to a retarded position, as shown in Figure 5, by removing the screw 6 from the engaged hole 7 of the disk 8 and engaging it in the other hole 7 of the disk.

40 The front and rear distributor and form roller units are operative units when the form roller frames are in their upper positions with the form rollers out of contact with the form, the distributor rollers retaining their contact with the form rollers and the pinions 63 retaining their mesh with the gear 61 and the pinion 69 retaining its mesh with the gear 67, so that the front and rear roller groups are driven with the bed with the form rollers out of contact with the form.

45 In inking up the press the form roller frames are positioned in their upper positions by the eccentric shafts 76 and 79. With the press running ink is supplied to the front roller group by hand, and preferably to the rear roller group by hand as the doctor roller takes too long to accumulate sufficient ink on these rollers for printing. When sufficient ink is distributed on both 50 front and rear roller groups, the form rollers are permitted to contact the form for printing, whereupon the ink fountain supplies all of the ink.

55 While I have described and shown the preferred embodiment of my invention I do not wish 70 75

to be limited to the precise details of construction as changes may readily be made without departing from the spirit of my invention, but having thus described my invention, I claim as new and 5 desire to secure by Letters Patent the following:

1. In a reciprocating bed and cylinder printing press the combination with groups of form inking rollers disposed on opposite sides of the cylinder and overlapping in their contact with a form 10 on the bed and neither group completely covering the form, of distributor rollers for said form rollers, means for moving each group of form rollers out of contact with the form during the corresponding reversal of the bed and re-establishing said contact immediately thereafter while maintaining contact of the form rollers with said distributor rollers, means for supplying ink to the rollers disposed on the rear side of the cylinder, said bed carrying the sole source of ink supply 15 for the rollers disposed on the front side of the cylinder, and means for driving said form and distributor rollers with the bed.
2. In a reciprocating bed and cylinder printing press the combination with groups of form inking rollers disposed on opposite sides of the cylinder and overlapping in their contact with a form on the bed and neither group completely covering the form and the roller nearest the cylinder on the front side thereof completely covering the form, 20 of distributor rollers for said form rollers, means for moving said groups of form rollers out of contact with the form during the corresponding reversals of the bed and re-establishing said contact immediately thereafter while maintaining contact of said form rollers with said distributor rollers, means for supplying ink to the rollers disposed at the rear side of the cylinder, said form constituting the sole source of ink supply for the rollers disposed at the front side of the cylinder, 25 and means for driving said form and distributor rollers with the bed.
3. In a reciprocating bed and cylinder printing press the combination with groups of form inking rollers disposed on opposite sides of the cylinder and overlapping in their contact with a form on the bed and neither group completely covering the form, of means for angularly shifting the cylinder with reference to its timing with the bed from a retarded position, in which the roller 30 nearest the cylinder on the front side thereof completely covers the form, to an advanced position in which this roller does not completely cover a corresponding rearwardly extended form, and means for supplying ink to the rollers disposed at the rear side of the cylinder, said ink supply constituting the sole source of ink supply for all 35 of said rollers.
4. In a reciprocating bed and cylinder printing press the combination with groups of form inking rollers disposed on opposite sides of the cylinder and overlapping in their contact with a form on the bed and neither group completely covering the form, each group being sufficient in number to adequately ink the form and comprising at least 40 three, of distributor rollers for said groups, means for moving said groups of form rollers out of contact with the form during the corresponding reversals of the bed and re-establishing said contact immediately thereafter while maintaining contact of said form rollers with said distributor rollers, means for angularly shifting the cylinder with reference to its timing with the bed from a retarded position, in which the roller nearest the cylinder on the front side thereof completely 45 covers the form, to an advanced position in which

this roller does not completely cover a correspondingly rearwardly extended form, means for supplying ink to a distributor roller of the group of form rollers disposed at the rear of the cylinder, said form constituting the sole source of ink supply to the rollers disposed at the front of the cylinder, and means for driving said form and distributor rollers with the bed.

5. In a reciprocating bed and cylinder printing press the combination with groups of form inking rollers disposed at opposite sides of the cylinder and overlapping in their contact with a form on the bed and neither group completely covering the form, of distributor rollers for said form rollers, means for moving each group of form rollers out of contact with the form during the corresponding reversals of the bed and re-establishing said contact immediately thereafter while maintaining contact of the form rollers with said distributor rollers, means for supplying ink to the rollers at the rear side of the cylinder, said form constituting the sole source of ink supply for the form rollers at the front side of the cylinder, means for driving said form and distributor rollers with the bed, and manually actuated means for positioning said form rollers out of contact with the form while maintaining contact of the form rollers with said distributor rollers.

6. In a printing press the combination with a distributor ink roller, a second roller periodically contacting said distributor roller, and an ink fountain ductor roller periodically contacting said second roller and when said second roller is contacting said distributor roller.

7. In a printing press the combination with a distributor ink roller, a second roller of relatively small diameter bodily movable into and out of contact with said distributor roller and yieldably urged out of contact therewith, and an ink fountain ductor roller periodically contacting said second roller and moving it into contact with said distributor roller.

8. In a printing press the combination with a group of form inking and distributor rollers, an additional roller of relatively small diameter, bearings for said additional roller permitting bodily movement thereof into and out of contact with a distributor roller of said group, said additional roller being yieldably urged out of contact with said distributor roller, an ink fountain, a ductor roller, and means whereby said ductor roller alternately contacts the roller of said fountain and said additional roller and moves said additional roller into contact with said distributor roller.

9. In a printing press the combination with a pair of form inking rollers, of a distributor roller contacting the same, a second distributor roller contacting said first mentioned distributor roller, an additional roller periodically contacting said second distributor roller, an ink fountain, a ductor roller, and means whereby said ductor roller alternately contacts the roller of said fountain and said additional roller when said additional roller is contacting said second distributor roller.

10. In a reciprocating bed and cylinder printing press the combination with three form inking rollers, of a distributor roller contacting the outer and intermediate of said form rollers, a second distributor roller contacting only the inner of said form rollers, a third distributor roller contacting said first mentioned and second distributor rollers, an additional roller periodically contacting said third distributor roller, an ink fountain spaced outwardly and upwardly from the

outer form roller, a ductor roller, and means whereby said ductor roller alternately contacts the roller of said fountain and said additional roller when said additional roller is contacting 5 said third distributor roller.

11. In a reciprocating bed and cylinder printing press the combination with three form inking rollers, of an ink fountain adjacently spaced upwardly and outwardly from the outer form roller 10 of said group, a distributor roller contacting the intermediate and inner of said form rollers, a second distributor roller contacting the intermediate and outer of said form rollers, a third distributor roller contacting said first mentioned distributor 15 roller, a ductor roller, and means whereby said ductor roller is movable above said outer form and said second distributor rollers for supplying ink from said ink fountain to said form and distributor rollers.
12. In a reciprocating bed and cylinder printing 20 press the combination with three form inking rollers, of an ink fountain adjacently spaced upwardly and outwardly from the outer form roller of said group, a distributor roller contacting the intermediate and inner of said form rollers, a second distributor roller contacting the intermediate and outer of said form rollers, a third distributor roller contacting said first mentioned distributor roller, an additional roller of relatively 25 small diameter periodically contacting said third distributor roller, a ductor roller, and means whereby said ductor roller is movable above said outer form and said second distributor rollers to alternately contact the roller of said fountain and 30 said additional roller when said additional roller is contacting said third distributor roller.

13. In a reciprocating bed and cylinder printing 35 press the combination with four form inking rollers for inking a form on the bed, of a distributor roller contacting the two intermediate rollers of said group, a second distributor roller contacting the outer and the adjacent intermediate roller of said group, a third distributor roller contacting only the inner form roller of said 40 group, a fourth distributor roller contacting said first mentioned and third distributor rollers, and means for periodically supplying ink to said fourth distributor roller.

14. In a reciprocating bed and cylinder printing 45 press the combination with four form inking rollers for inking a form on the bed, of an ink fountain adjacently spaced upwardly and outwardly from the outer form roller of said group, a distributor roller contacting the two intermediate rollers of said group, a second distributor roller contacting the outer and the adjacent intermediate roller of said group, a third distributor roller contacting only the inner form roller of said 50 group, a fourth distributor roller contacting said first mentioned and third distributor rollers, an additional roller of relatively small diameter periodically contacting said fourth distributor roller, a ductor roller, and means whereby said ductor roller is movable above said outer form 55 and said second distributor rollers to alternately contact the roller of said fountain and said additional roller when said additional roller is contacting said fourth distributor roller.

15. In a reciprocating bed and cylinder printing 60 press the combination with a group of form inking rollers, of an ink fountain adjacently spaced outwardly and upwardly from the outer form roller of said group, a ductor roller, a carrier for said ductor roller, and a bearing mount- 65 ing for said carrier for the movement of said 70

ductor roller above said outer form roller to and from said fountain and disassociated from said fountain whereby to provide space for the removal and installation of said outer form roller vertically past said fountain when said ductor roller is positioned away from said fountain. 5

16. In a reciprocating bed and cylinder printing 10 press the combination with a group of form inking rollers, of an ink fountain adjacently spaced outwardly and upwardly from the outer form roller of said group, a ductor roller, a carrier for said ductor roller and a pivot mounting for said carrier for the movement of said ductor roller above said outer form roller to and from said fountain and disposed above said form rollers and spaced from said fountain in the direction over said form rollers whereby to provide space for the removal and installation of said outer form roller vertically past said fountain when said ductor roller is positioned away from 20 said fountain.

17. In a reciprocating bed and cylinder printing 15 press the combination with a group of form inking rollers, of an ink fountain adjacently spaced outwardly and upwardly from the outer form roller of said group, a ductor roller, a carrier for said ductor roller, a pivot mounting for said carrier independent of said fountain and disposed above said form rollers in the region of said outer form roller for the movement of said 25 ductor roller above said outer form roller and to and from said fountain whereby to provide space for the removal and installation of said outer form roller vertically past said ink fountain when said ductor roller is positioned away from said 30 fountain, and fork bearings for said outer form roller and extending obliquely upward to guide 35 this form roller in the installation and removal of this form roller.

18. In a reciprocating bed and cylinder printing 40 press the combination with three form inking rollers, of an ink fountain adjacently spaced outwardly and upwardly from the outer form roller of said group, a distributor roller contacting the intermediate and inner form rollers, a second distributor roller contacting said outer and intermediate form rollers and having its axis disposed in the region of the plane of the axis of 45 said form rollers, a third distributor roller contacting said first mentioned distributor roller, an additional roller of relatively small diameter periodically contacting said third distributor roller, a ductor roller, a carrier for said ductor roller for the movement of said ductor above said outer form and said second distributor rollers to alternately contact the roller of said fountain and 50 said additional roller when said additional roller is contacting said third distributor roller, and a pivot mounting for said carrier disposed above said form rollers in the region of said outer form roller and providing space for the removal and installation of said outer form roller vertically past said fountain when said ductor roller is positioned away from said fountain. 55

19. In a printing press the combination with 60 a pair of adjacently spaced form inking rollers, of a distributor roller therebetween and contacting the same and having its axis in the region of the axial plane of said form rollers, bearings for said distributor roller and mounted for adjustment of said distributor roller in directions corresponding with said axial plane, a second distributor roller contacting one of said form rollers, and means for driving said second distributor roller with the bed. 65

20. In a printing press the combination with a group of form inking rollers, of a distributor roller contacting an adjacent pair thereof and having its axis in the region of the axial plane 5 of said form rollers, a second distributor roller contacting one of said pair and a third form roller, and means for driving only said second distributor roller.
21. In a printing press the combination with 10 four form inking rollers, of a distributor roller contacting the intermediate pair of said form rollers, two additional distributor rollers contacting respective of the outer form rollers and the form rollers adjacent thereto, and means for driving only said first mentioned distributor roller.
22. In a printing press the combination with 15 four form inking rollers, of a distributor roller contacting the intermediate pair of said form rollers, two additional distributor rollers contacting respective of the outer form rollers and the form rollers adjacent thereto and having their axes disposed in the region of the axial plane of said form rollers, and means for driving only said first mentioned distributor roller.
23. In a printing press the combination with 20 a group of form inking rollers, of a frame carrying the same, a distributor roller carried with said frame and contacting an adjacent pair of 25 said form rollers, a second distributor roller contacting one of said pair and a third form roller, a second frame carrying said second distributor roller and movable with reference to said first mentioned frame to disengage said second distributor roller from its form rollers, and gearing for driving said second distributor roller and permitting movement of said second frame.
24. In a printing press the combination with a group of form inking rollers, of a frame carrying the same, a distributor roller carried with 30 said frame and contacting an adjacent pair of said form rollers and having its axis disposed in the region of the axial plane of said form rollers, means whereby said distributor roller is carried by said frame for adjustment in directions corresponding with the axial plane of said form rollers, a second distributor roller contacting one of said pair of form rollers and a third form roller, a second frame carrying said second distributor roller and pivotally movable with 35 reference to said first mentioned frame to disengage said second distributor roller from its form rollers, and gearing for driving said second distributor roller and permitting movement of said second frame.
25. In a printing press the combination with 40 four form rollers, of a frame underlying the axes of said form rollers and carrying the same and provided with upwardly extending supports between the axes of an outer pair of said form rollers, a distributor roller contacting the intermediate pair of said form rollers, two additional distributor rollers carried with said frame and contacting respective of the outer form rollers, and the form rollers adjacent thereto, a second frame carrying said first mentioned distributor roller and pivotally mounted on said supports to disengage said first mentioned distributor roller from its form rollers, and gearing for driving 45 said first mentioned distributor roller and permitting movement of said second frame.
26. In a printing press the combination with four form rollers, of a frame underlying the axes of said form rollers and carrying the same and provided with upwardly extending supports be- 50 tween the axes of an outer pair of said form rollers, a distributor roller contacting the intermediate pair of said form rollers, two additional distributor rollers contacting respective of the outer form rollers, and the form rollers adjacent thereto and having its axis in the region of the axial plane of said form rollers, and bearings for 55
27. In a reciprocating bed and cylinder printing press the combination with a group of form inking rollers at one side of the cylinder, of a frame underlying the axes of said form rollers and carrying the same and provided with upwardly extending supports between the axis of the outer form roller and that of the adjacent form roller, a second frame pivoted on said supports above said form rollers, a distributor roller carried by said second frame for contacting said adjacent form roller and another form roller inwardly adjacent the same, and a second distributor roller carried with 60 said first mentioned frame and contacting said outer form roller and the form roller adjacent thereto and having its axis in the region of the axial plane of said form rollers.
28. In a reciprocating bed and cylinder printing press the combination with a group of form inking rollers at one side of the cylinder, of a frame underlying the axes of said form rollers and carrying the same and provided with upwardly extending supports between the axis of the outer form roller and that of the adjacent form roller, a second frame pivoted on said supports above said form rollers, a distributor roller carried by said second frame for contacting said adjacent form roller and another form roller inwardly adjacent the same, a second distributor roller carried with said first mentioned frame and contacting said outer form roller and the form roller adjacent thereto and having its axis in the region of the axial plane of said form rollers, an ink fountain adjacently spaced outwardly and upwardly from said outer form roller, a ductor roller, and a carrier for said ductor roller and pivoted on said supports above said form rollers for movement of the ductor roller for transferring ink from 65 said fountain.
29. In a reciprocating bed and cylinder printing press the combination with a group of form rollers at one side of the cylinder, of a frame underlying the axes of said form rollers and carrying the same and pivoted outwardly from said cylinder and provided with upwardly extending supports between the axis of the outer form roller and that of the adjacent form roller, means for pivotally moving said frame to position said form rollers out of contact with a form on the bed during the reversal of the bed in which said form underlies said form rollers, a second frame pivoted on said supports above said form rollers, a distributor roller carried by said second frame for contacting said adjacent form roller and another form roller inwardly adjacent the same, a second distributor roller between and contacting said outer form roller and the form roller adjacent thereto and having its axis in the region of the axial plane of said form rollers, and bearings for 70
- 75

said second distributor roller and adjustably mounted on said supports for adjustment of this roller in directions corresponding with the axial plane of said form rollers.

- 5 30. In a reciprocating bed and cylinder printing press the combination with a group of form inking rollers at one side of the cylinder, of a frame underlying the axes of said form rollers and carrying the same and provided with upwardly extending supports between the axis of the outer form roller and that of the adjacent form roller, means for pivotally moving said frame to position said form rollers out of contact with a form on the bed during the reversal of the bed in which 10 15 said form underlies said form rollers, a second frame pivoted on said supports above said form rollers, a distributor roller carried by said second frame for contacting said adjacent form roller and another form roller inwardly adjacent the same, a second distributor roller between and contacting said outer form roller and the form roller adjacent thereto and having its axis in the region of the axial plane of said form rollers, bearings for said second distributor roller and 20 25 movably mounted on said supports for adjustment of this roller in directions corresponding with the axial plane of said form rollers, an ink fountain adjacently spaced outwardly and upwardly from said outer form roller, a ductor roller, and a carrier for said ductor roller and pivoted on said supports above said form rollers for movement of the ductor roller for transferring ink from said fountain.
31. In a printing press the combination with a 35 40 form inking roller, of a frame carrying said form roller and pivotally movable to engage and disengage said form roller with a form on the bed, of a distributor roller, a second frame carrying said distributor roller and pivotally mounted on said first mentioned frame to engage and disengage said distributor roller with said form roller, releasable means for locking said frames together with said distributor roller contacting said form

roller, manually controlled means for positioning said first mentioned frame, while said form roller is in contact with said distributor roller, with said form roller in or out of contact with said form, and gear means for driving said distributor roller while said frames are locked together and permitting said movement of said second frame with reference to said first mentioned frame.

5 32. In a reciprocating bed and cylinder printing press the combination with a roller frame pivotally mounted for movement to engage and disengage form rollers carried by the frame with a form on the bed, means controlled by the bed for positioning said frame to disengage said form rollers from the form during a reversal of the bed in 10 15 which the form underlies said form rollers and to re-establish said engagement immediately thereafter, and manually actuated means for positioning said frame with said rollers disengaged from the form.

33. In a reciprocating bed and cylinder printing press the combination with a form roller frame pivoted for vertical movement on a transverse horizontal axis, a distributor roller frame pivoted on said form roller frame on a corresponding axis, and normally moving therewith, a pair of horizontally spaced distributor ink rollers on said distributor roller frame and contacting form rollers on said form roller frame, a driving gear having its axis disposed below said distributor rollers and so that an arc of the pivotal axis of said form roller frame and passing through the axis of said driving gear passes between the axes of said distributor rollers, pinions on said distributor rollers and meshing with said driving gear, and means for lifting said form roller frame, while maintaining the mesh of said pinions with said driving gear, during a reversal of the bed in which a form thereon underlies said form rollers and lowering said form roller frame 40 immediately thereafter.

ROBERT MIEHLE.
